UNITED STATES PATENT OFFICE.

ROBERT HINCKLEY, OF WASHINGTON, DISTRICT OF COLUMBIA.

DESIGN FOR A BABY'S CAP.

SPECIFICATION forming part of Design No. 83,211, dated September 18, 1900.

Application filed July 26, 1900. Serial No. 24,950. Term of patent 3½ years.

To all whom it may concern:

Be it known that I, ROBERT HINCKLEY, a citizen of the United States, residing at Washington city, in the District of Columbia, have 5 invented and produced a new and original Design for a Baby's Cap; and I do hereby declare the following to be a full, clear, and exact description of the same, reference being had to the accompanying drawings, forming a part 10 thereof.

Referring to the drawings, Figure 1 is a perspective view showing my design, and Fig. 2 is a side elevation of the same.

The leading or material feature of my design 15 consists of the configuration of the side portions A A of the cap and their position relative to the crown B. The sides are formed from a single piece of material which sur-

rounds the crown, forming the front portion of the cap and lower and rear portion or base. 20 This shape of the piece forming the sides of the cap gives nearly a straight edge to the base of the cap, while its front side edges are carried outwardly and forwardly near their lower ends, as denoted at a, giving greater 25 width and length at the sides where they would bear upon the baby's ears.

I claim—

The design for a baby's cap substantially as shown and described. 30

In testimony whereof I affix my signature in presence of two witnesses.

ROBERT HINCKLEY.

Witnesses:

CHARLES BRIGHAM,
JOHN J. CHEW.
